FLOOR SURFACING MACHINE

Richard F. Kneisley and Robert E. Wolfe, Toledo, Ohio, assignors to The American Floor Surfacing Machine Company, Toledo, Ohio, a corporation of Ohio

Application May 20, 1938, Serial No. 209,089

10 Claims.

(CL 51—176)

This invention relates to floor surfacing machines, and more particularly to those of the sanding type.

The primary object of the invention is the provision of a machine of this character, which has its frame or enclosing casing so constructed as to simplify and cheapen the cost of manufacture, also to enable the frame parts to be easily and quickly assembled and to permit easy and rapid mounting of the working parts of the machine in the frame, whereby to enhance the practicability and commercial value thereof.

A further object of the invention is to provide a compact, shallow machine of this character with the operating parts, including the motor, sand drum and dust collecting means mounted therein, one back of another, and entirely enclosed by the frame housing.

A further object of the invention is the provision of an improved dust collecting means for machines of this character, whereby dust may be introduced up into a receptacle and distributed uniformly over its bottom, which is preferably of considerable area, and which receptacle may be easily and quickly removed from the machine for the purpose of cleaning without any accidental loss of dust therefrom.

Other objects and advantages of the invention will be apparent from the following detailed description and from the accompanying drawings, in which—

Figure 1 is a side elevation of a machine embodying the invention, with parts broken away; Fig. 2 is a top plan view thereof, with parts broken away; Fig. 3 is a perspective view of the machine, with the removable hood and front closure member of the housing removed from the machine frame; Fig. 4 is a perspective view of the removable hood and front end closure member separate from the machine; Fig. 5 is a section on the line 5—5 in Fig. 1, with parts in full; and Fig. 6 is an enlarged detailed section on the line 6—6 in Fig. 1.

Referring to the drawings, 1 designates the housing of a machine including the invention, such housing being of comparatively shallow box form and having a substantially flat top which is coextensive, or substantially so, with the horizontal cross-sectional area of the machine, and which has depending sides and ends forming a protecting skirt around the major working parts. The flat top of the housing provides a rest for the dust collecting bag 2, which has removable connection with the dust fan conduit through the

frame top substantially centrally thereof, as hereinafter described.

The housing 1 comprises a U-shaped body frame section 3 disposed in reclining position with its legs transversely spaced in a horizontal plane 5 and forming the sides of the frame body, and with its loop portion disposed at and forming the rear closed end of such body, as best shown in Fig. 3. This frame section is preferably made from heavy sheet metal or broad bar stock to 10 give it strength and rigidity, and has bearings in the top edge portions of its sides for the frame trunnions 4 of an electric motor 5, the shaft of which is horizontally disposed and projects beyond one side of the frame where it carries a 15 pulley 6. The trunnions 4 are retained in their bearings by straps 7.

The rear end of the housing 1 is formed above the frame section 3 by a rear end member, which seats on the upper edge of the looped portion of the body frame, being provided at its lower edge with an offset flange which fits into and is secured to said loop portion by screws 9. The member 8 is of hood form, being provided with forwardly extending top and side portions which terminate at the rear of the motor and have an inwardly offset lip flange 10. This member is of rigid construction, being preferably a casting and has the handle 11 attached thereto, in the present instance, by insertion into a socket part 12 to which it is bolted.

Between the leg portions of the body frame 3, at their front or free ends, is mounted a sanding drum 15, the shaft 16 of which is mounted at its ends in suitable bearings 17 in the frame legs. 35 One end of such shaft projects without the frame and carries a pulley 18 in driven connection with the motor pulley 6 through a belt 19. The drum 15 projects slightly below the lower edge of the frame 3.

The fan means 20 of the dust collecting system is disposed intermediate the motor 5 and sanding drum 15 between the legs of the frame member 3, being suitably supported therein, as by attaching its housing to such legs and to the motor 45 housing. The fan housing has the customary dust inlet mouth 21 opening adjacent to the lower rear portion of the sanding drum, as well understood in the art, and has the upwardly extending outlet neck 22 terminating in substantially the 50 top plane of the hood section 8. The fan has its shaft extending through one leg portion or side of the frame 3 and is driven by a belt 23 connecting a pulley 24 thereon with a pulley on the drum shaft, the other of which carries the belt 19.

40

45

50

55

The rear end of the frame member 2 is supported by a caster 25 attached to a flange 26 at the inner side of the loop portion of said frame, and the frame is supported in advance thereof 5 at substantially its center by a pair of vertically adjustable wheels 27 carried by the arms of a yoke 28 mounted on a cross-shaft 29, as well understood in the art. The yoke 28 has a rearwardly extending arm 30 connected by a rod 31 to a control lever 32 on the handle 11, whereby the engagement of the sanding drum with the surface being sanded may be controlled.

The top of the housing 1 is closed in advance of the rear hood section 8 by a top hood section 35 15 of inverted U-form in vertical cross-section, which seats at its side edges on the top edges of the leg portions of the body frame 3, and at its rear edge fits over and is secured to the lip flange 10 of the hood section 8 by screws 36. The side edges of the hood section 35 are provided with inwardly offset downwardly projecting legs 37 for engaging the inner top side edges of the frame 3.

The front end of the housing 1 is closed by a front section 40, which has its side and top edges 25 inwardly extended to seat against the front ends of the body frame 3 and top hood section 35. The section 40 is hinged at its top edge to the front end of the hood section, as shown at 41 (Fig. 4) to facilitate access to the drum 15 when changing 30 the sanding paper thereon. The hood section 35 is provided near its forward end with a handle 42 and has an opening 43 for registering with and receiving the upper open end of the fan housing outlet neck 22.

35 The dust bag 2 has a rather large bottom portion for resting on the top of the hood section 35 and is provided through its bottom with an inlet tube 45 to which the bag mouth is closely clamped, as by a band 46. The tube 45 has its lower end projecting a short distance below the bag and in suitable position to register with and be fitted into the outlet neck 22 of the fan housing. The tube extends a distance up into the bag and is provided with a dust deflecting disk 47 in upwardly spaced relation to the tube end, so that the discharging dust is directed laterally in all directions from the tube and deposited uniformly in the bottom of the bag around the tube. The projecting of the tube 45 up into the bag is an important feature, as it enables the operator, in removing a bag, to grasp the top portion of the tube through the intermediate upper collapsed portion of the bag and to withdraw the tube from the neck 22 without spilling any of the dust from 50 the bag through the inlet opening. One end of the bag is preferably provided with a zippered opening (not shown) to facilitate dumping of its contents.

The pulleys and belts which connect the motor 60 to the drum and fan means are disposed without one side of the machine housing and are enclosed and protected by a guard 50 which, in the present instance, comprises three sections a, b and c. The section a is attached to the hood section 8; 65 the section b is attached to the hood section 35 and extends outwardly and downwardly from a side edge thereof in skirt form, and the section c is attached to the front end section 40.

It is apparent that the present invention provides a housing structure for a floor surfacing machine, which housing is of simple, compact and shallow form and encloses as well as supports all of the operative parts of the machine in convenient arrangement and has portions thereof 70 easily and quickly removable to render access to

the operating parts; also that in this machine the motor sets low at the rear of the other operating parts and is enclosed within the housing; also that with such arrangement of operating parts it is possible to have a shallow form of housing 5 with a substantially broad flat top on which the dust collecting bag alone may be mounted.

We wish it understood that our invention is not limited to any specific construction, arrangement or form of the parts, as it is capable of numerous modifications and changes without departing from the spirit of the claims.

Having thus described our invention, what we claim as new and desire to secure by United States Letters Patent is:

1. In a machine of the class described, an open bottom housing comprising a U body frame with its open end forward and carrying the operating parts of the machine, a rear hood section fixedly mounted on the rear closed end of said frame and forming a rigid frame structure therewith, a top hood section of inverted U-form in cross-section removably mounted on the leg portions of said body frame and cooperating with the rear hood section to close the top of the body frame, and a front section movably attached to the front end of said top section and adapted to close the same and the front end of the body frame.

2. In a machine of the class described, an open bottom housing comprising a U body frame of 30 shallow form and formed of plate or bar stock with its open end forward and its legs horizontally spaced, said frame having the operating parts of the machine mounted therein, a top hood portion substantially U-form in cross-section 35 mounted on said frame with its legs seating on the top edges of the respective legs of said frame, said hood portion cooperating with said frame to close the rear end of the housing and having its forward end open, and a forward housing section attached to the forward end of said hood and adapted to close its forward end and that of the frame.

3. In a machine of the class described, a shallow U body frame with its open end forward and its legs horizontally spaced, a sanding drum disposed between the forward ends of the frame, with its shaft transverse to and journaled in the legs, an electric motor disposed in the rear end portion of the frame between its legs with its shaft transverse thereto, the motor housing being mounted in the frame between its legs, dust collecting fan means mounted in the frame between said drum and motor with a dust receiving mouth adjacent to said drum and an upwardly directed 45 outlet, means for driving the drum and fan from the motor, a hood mounted on said frame and cooperating therewith to form a substantially flat top casing closed at sides, top and rear, and a separate casing part closing the front end of 50 said casing and movable to render access to the front of the drum.

4. In a machine of the class described, a shallow U body frame disposed in horizontal position with its open end forward and its leg portions 65 forming the frame sides, a sanding drum, a dust collecting fan means and a motor supported by and mounted between the legs of said frame one back of another, means mounted on and forming a shallow cover over said frame and forming a 70 substantially flat top surface over the major portion of the frame and units mounted therein and having an opening through such top in communication with said means, and a dust receiving receptacle resting at its bottom on said top 75

in surrounding relation to said opening and having dust receiving communication with the opening.

5. In a machine of the class described, a shallow housing open at its under side and having a substantially flat top of considerable area with a dust delivery opening therethrough, a sanding drum, a dust collecting fan means and a motor mounted in said housing below said top, means 10 cooperating with said drum to support said housing, and a dust receiving bag having a bottom of considerable area resting on said housing top around said opening, said bag having communication through its bottom with said opening.

15. 6. In a machine of the class described, a shallow housing open at its under side and having a substantially flat top of considerable area with a dust delivery opening therethrough, a sanding drum, a dust collecting fan means and a motor 20 mounted in said housing below said top, means cooperating with said drum to support said housing, and a dust receiving bag having a bottom of considerable area resting on said housing top around said opening, and a tube releasably joined 25 at its lower end to said opening and extending a distance up into the bag with its upper end opening therein.

7. In a machine of the class described, a shallow housing open at its under side and having 30 a top which is substantially flat through the horizontal area of the housing and having an opening therethrough adjacent to its center, a sanding drum, a dust collecting fan means and a motor mounted in said housing with the fan means near 35 the center of the frame and outlet in communication with said opening, a dust bag having a broad bottom for resting on said top in surrounding relation to said opening and having a dust delivery tube projecting upward therein and 40 connected at its lower end to said opening.

8. In a machine of the class described, a shallow housing open at its bottom and having a substantially flat top of considerable area with an opening therethrough in spaced relation to the side edges of the top, a sanding drum and 5 dust collecting fan means mounted within said housing, a motor carried by the frame for driving said drum and means, and a dust receiving bag having a broad bottom portion resting flat on said top in surrounding relation to said opening and having inlet communication through its 10 bottom with said opening.

9. A floor surfacing or like machine, including a housing composed of a base and a cover, said base being of substantially U-form in top plan 15 view, and having a member at its rear end for connection with a handle, the legs of the base being of less height than that of the height of the housing and being adapted to support the operating parts of the machine so as to locate 20 the center of gravity close to the surface on which the machine operates, the cover being of substantially U-shape in cross-section and engaged with the member at the rear end of the latter, and a front member movably connected 25 to the cover to close the front end of the latter and the free ends of the legs of the base.

10. A floor surfacing or like machine in accordance with claim 9 wherein the member at the rear of the base has a top, a closed rear end, 30 and closed sides, and with its front end open, and wherein the cover has the rear end thereof, engaging the top and side portions of the member, and wherein the movable front member has a top hingedly connected to the top of the cover 35 and has sides engaging the front ends of the sides of the cover.

RICHARD F. KNEISLEY.

ROBERT E. WOLFE.
